UNITED STATES PATENT OFFICE.

EDWIN F. BEUGLER, OF BUFFALO, NEW YORK, ASSIGNOR TO E. & B. HOLMES MACHINERY COMPANY, OF BUFFALO, NEW YORK, A CORPORATION OF NEW YORK.

MACHINE FOR LOCKING METAL HOOPS.

1,286,210.

Specification of Letters Patent.

Patented Dec. 3, 1918.

Application filed October 5, 1915. Serial No. 54,169.

To all whom it may concern:

Be it known that I, EDWIN F. BEUGLER, a citizen of the United States, residing at Buffalo, in the county of Erie and State of New York, have invented new and useful Improvements in Machines for Locking Metal Hoops, of which the following is a specification.

This invention relates to a machine for locking or connecting the ends of sheet metal barrel hoops and has the object to produce a machine for this purpose which is strong and durable in construction, efficient in operation and which will permit of properly and reliably locking or joining the ends of a comparatively large number of hoops within a given time and with a minimum expenditure of power so as to enable hoops of this character to be locked more economically and advantageously than has been possible heretofore.

In the accompanying drawings:

Figure 1 is a front elevation of a machine for locking hoops embodying my invention. Fig. 2 is a top plan view of the same with parts broken away. Fig. 3 is a side elevation at the right hand side thereof with parts broken away. Fig. 4 is a vertical longitudinal section of a machine taken in line 4—4, Fig. 1. Fig. 5 is a fragmentary transverse section taken on line 5—5, Fig. 4. Fig. 6 is a fragmentary vertical longitudinal section, on an enlarged scale, taken in line 6—6, Fig. 2 and showing the position of the parts of the locking forming devices preparatory to forming the first step in producing the lock between the ends of a metal barrel hoop. Fig. 7 is a similar view of parts of the lock forming devices showing the same in the position which they occupy while effecting the first step of the lock forming operation. Fig. 8 is a similar view showing the position of the parts of the lock forming devices preparatory to performing the second step of the lock forming operation. Fig. 9 is a similar view showing the position of these parts while performing the second step of the lock forming operation. Fig. 10 is a face view of the movable block which carries the rivet forming and clenching dies and one of the hook forming cutters. Fig. 11 is a face view of the stationary block which carries the rivet abutment dies and the other hook forming cutter. Fig. 12 is a horizontal section taken on line 12—12,

Fig. 10. Fig. 13 is a horizontal section on line 13—13, Fig. 11. Fig. 14 is a fragmentary vertical longitudinal section taken on line 14—14, Fig. 13. Fig. 15 is a fragmentary view of the overlapping ends of a sheet metal hoop showing the same connected by the lock or joint which is produced by my improved locking machine. Fig. 16 is a longitudinal section thereof taken on line 16—16, Fig. 15. Figs. 17 and 18 are vertical transverse sections taken on the correspondingly numbered lines in Fig. 15. Similar characters of reference indicate corresponding parts throughout the several views.

Although the particular form of the lock or joint which is produced by this machine for connecting the ends of a sheet metal hoop may be varied the same, as shown in Figs. 15—18, preferably comprises two rivets 1 which connect the overlapping ends 2, 3 of a sheet metal hoop and a plurality of interlocking hooks or lips, 4, 5 formed respectively on these hoop ends. Each of the rivets is formed integrally from the stock from which the hoop ends are made by piercing and punching or displacing the metal thereof so as to produce two eyelets which are arranged concentrically one within the other, the outer eyelet being formed on the outer hoop end and upset against the outer side of the same and the inner eyelet extending from the inner hoop end outwardly through the outer eyelet and upset at its front end against the outer end of the outer eyelet. For some purposes these eyelet rivets may be sufficient to lock the hoop ends both against lateral and longitudinal displacement relatively to each other, but when the use to which the hoop is to be put requires the same to resist extra heavy longitudinal strains it is preferable to supplement the holding effect of the eyelet rivets by means of a supplemental locking device which comprises a plurality of outwardly projecting hooks 4 arranged in a longitudinal row on the inner hoop ends and engaging with their noses against the shoulders formed on the outer hoop end adjacent to the noses of its hooks, as shown in Fig. 16. These interlocking hooks of the hoop ends are produced by a longitudinal row of vertical slits formed in the hoop ends between the eyelet rivets and displacing the metal adjacent to these slits outwardly a sufficient distance to per-

mit the nose of the hooks on the inner hoop end to engage with the shoulders opposite the nose of the hooks on the other hoop ends.

The main frame of this machine for forming this lock joint between the hoop ends may be variously constructed to support the various working parts but as shown in the drawings the same comprises essentially two upright side pieces or standards 6, 6 which are arranged lengthwise of the machine, a plurality of horizontal transverse cross bars 7 connecting the lower parts of the side pieces and a table or top 8 connecting the upper ends of these side pieces.

15 Preparatory to producing the lock or joint between the ends of a hoop the latter is placed upon a mandrel with its ends overlapping each other and then the hoop is expanded to its proper size and its overlapping ends are securely held in place relatively to each other so that the lock which is subsequently produced on the same will be in its proper position and also produce a hoop of a definite size. This mandrel may 20 be variously constructed but in its preferred form the same is adapted to support the hoop in a horizontal position during the lock forming operation. As shown in the drawings, this mandrel preferably comprises a normally stationary front section which is of substantially semi-circular form and a rear section of substantially semi-circular form which is movable radially relatively to the front section. The normally fixed front mandrel section comprises a cross piece 9 which is detachably secured to the table by a vertical clamping bolt 10, two curved upright flanges or walls 11 arranged at opposite ends of the cross piece 25 and separated from each other by an intervening space or gap and horizontal flanges 211 projecting outwardly from the curved flanges. The rear mandrel section comprises an upright curved flange or wall 12 and a horizontal flange 13 projecting outwardly from the lower edge of the upright flange 12. Preparatory to applying the hoop on the mandrel the rear movable mandrel section is moved forward so as to reduce the diameter of the mandrel and permit of placing the hoop thereon so that the same surrounds the vertical flanges of the mandrel sections and rests with its lower edge on their horizontal flanges which latter form supporting shoulders or shelves for this purpose. The hoop is placed upon the mandrel with its ends overlapping each other in the space between the front flanges 11, 11 and held together by a gripping device which will be hereinafter explained.

30 After the hoop has been thus placed over the contracted mandrel the rear mandrel section is moved rearwardly so that the upright flanges of the several mandrel sections engage firmly with the inner side of the

hoop and expand the latter until the required diameter of hoop has been reached for which the machine has been set. During this expanding operation the overlapping ends of the hoop which at this time are 70 only held frictionally in engagement with each other are permitted to slip relatively to each other the required extent. After the hoop has been thus sized as to its diameter the locking devices operate upon the overlapping ends of the hoops and form a connection between the same which operates to hold these ends against displacement both lengthwise and transversely so that the hoop is ready for use. After the lock has 75 been produced on the overlapping ends of the hoops the rear mandrel section again moves forwardly so as to contract the mandrel as a whole and permit the operator to remove the finished hoop and replace the 80 same by another unfinished hoop. During the radial movement of the rear mandrel section the same is guided, this being preferably effected by providing the opposite ends of this mandrel section with laterally 85 projecting guides lugs 14 which slide upon the upper sides of horizontal guide rails 15 arranged lengthwise upon the table of the frame on opposite sides of the mandrel.

The means for effecting this radial movement of the rear mandrel section may be variously designed but as shown in the drawings these means comprise a horizontal rock shaft 16 journaled transversely in suitable bearings on the rear part of the main frame 100 and having an upper arm 17 which is operatively connected with the rear mandrel section and a lower arm 18 which is provided with a roller 19, a main shaft 20 journaled horizontally and transversely in suitable bearings on the lower central part of the machine, and a cam 21 which is secured to the shaft 20 and which engages with a roller 19 on the arm 18 for turning the sizing lever in the direction which will move 105 the rear mandrel section radially outward. The weight of the lower arm of this sizing lever is sufficiently heavy to turn the same in the opposite direction and move the rear mandrel section radially inward when 110 the low part of the sizing cam 21 is presented to the roller 19.

Means are preferably provided which will permit the connection between the sizing lever and the rear mandrel section to yield 115 when a resistance is offered to the expansion of the mandrel in excess of that for which the machine is designed to withstand and thereby prevent breakage of parts under abnormal strains. This will be liable to occur 120 if the operator places a previously locked hoop of a smaller size in the machine before the same is re-adjusted to operate upon hoops of a larger size, in which case the operating mechanism for the rear mandrel 125

would be subjected to undue strain. To guard against breakage or accidents under these circumstances a yielding device is provided which preferably consists partly in 5 forming the upper arm of the sizing lever in two sections 23, 24 which are pivotally connected with each other by a horizontal transverse bolt 25, the lower section being connected with the lower arm 18 of this lever 10 while the upper section is operatively connected with the rear mandrel section. The arm section 23 is yieldingly pressed rearwardly against a stop 26 on the lower section 24 by means of a spring device so that 15 these two arm sections are practically rigid during the normal operation of the machine. This spring device, as shown in Figs. 3, 4 and 5 preferably comprises a tension rod 27 passing through the upper arm section 23 20 and the stop 26 thereof and provided at its inner end with a screw nut 28 engaging with the inner side of the arm section 23 and a spring 30 surrounding the tension rod 27 and bearing at its inner end against the outer 25 side of the stop 26 and at its outer end against an outer screw nut 29 on the rod 27. If the rear mandrel section during its rearward movement encounters abnormally high resistance the lower section 24 of the upper 30 sizing lever arm moves rearwardly independently of the upper section 23 during which time the spring 30 is compressed and during the return movement of these parts this spring again restores these parts to 35 their normal position, thereby avoiding accidents under the abnormal conditions referred to. The inward or return movement of the rear mandrel section and the parts connected therewith is limited by means of 40 a stop 31 mounted on the lower section of the upper arm of the sizing lever and adapted to engage with the upper rear part of the main frame, as shown in Fig. 4.

For the purpose of enabling this machine 45 to be used for sizing and locking the sheet metal hoops of different diameters a plurality of sets of different sizes of mandrel sections are provided which sets are capable of being interchanged in the machine in accordance with the particular size of hoop desired. The interchange of the front mandrel sections is readily accomplished by 50 means of the clamping bolt 10 whereby the front sections are detachably connected with the main frame. For the purpose of detachably connecting the rear sections of the mandrel sets with the operating mechanism of the machine means may be provided of various constructions but as shown in the 55 drawings these means are preferably constructed as follows:

32 represents a shifting rod arranged horizontally and lengthwise in the upper rear part of the machine and connected at 60 its front end with the central part of the

rear mandrel section while its rear end is provided with an external screw thread. 33 represents a coupling lug or sleeve which is mounted on the threaded rear part of this shifting rod and adapted to be adjusted 70 lengthwise thereon by means of two screw nuts 34, 35 working on the thread of the shifting rod and engaging with the front and rear ends of the coupling lug 33. The latter is normally arranged between two 75 rocking lugs 36 arranged on the upper end of the upper section 23 of the upper arm of the sizing lever. The shifting rod lug and the sizing lever lugs are detachably connected with each other by means of a 80 locking pin or coupling bolt 37 passing horizontally through corresponding openings in these lugs. One end of this locking bolt is provided with a handle 38 for manipulating the same and its opposite end is 85 pointed and provided on one side with a notch 39 which is adapted to be engaged by a spring catch 40 which is guided vertically in a way 41 on the arm section 23 and normally pressed upwardly by means of a 90 spring 42 arranged in said guideway and bearing at its upper end against the lower end of the catch and at its lower end against a pin 43 arranged at the lower end of said guideway, as shown in Fig. 5. By running the screw nuts 34, 35 forwardly or backwardly the rear mandrel section may be accurately adjusted relatively to its actuating mechanism for expanding the hoop which is to be locked accurately to the diameter 95 which the same should have in its finished state and by means of the detachable connection between the shifting rod 32 and the upper arm of the sizing lever it is possible to quickly and conveniently change the machine for locking different sizes of hoops. In practice it is preferable to have a set of 100 mandrel sections for each size of hoops which are to be locked and provide the rear section of each set of mandrel sections with 105 a shifting rod 32 and coupling lug 33 which has been previously adjusted to secure the right size of hoops, thereby avoiding the necessity of producing any fine adjustments when changing from one size hoop to another. 110

During the operation of sizing the hoop and forming the locking joint between the overlapping ends thereof means are provided for securely holding these ends in 115 place relatively to each other which means are preferably constructed as follows:

44 represents a supporting head which is arranged in the gap between the upright and horizontal flanges of the front mandrel section and is formed on the front part of the frame table. The front side of this head is provided with an upright curved face which is substantially concentric with the upright flanges of the front mandrel 120 125 130

section so as to practically form a part of the means for internally supporting the hoops during the sizing and locking operations, this curved surface of the supporting head being adapted to engage with the inner side of the inner hoop end while the latter is engaged on its outer side by the outer hoop end. In practice it is preferable to have the left hand hoop end arranged on the inner side of the hoop and the right hand hoop end arranged on the outer side of the hoop, although the machine may be designed to operate upon the hoop ends reversely of this position, if desired.

45, 46 represent two clamping jaws which are arranged horizontally side by side in front of the supporting head, the left one 45 being provided with a smooth gripping face which is adapted to engage with the outer side of the left or inner hoop end adjacent to the right hand or outer hoop end, while the other or right hand clamping jaw 46 is provided with a roughened gripping surface which is adapted to engage with the outer side of the outer hoop end between the overlapping extremities of the hoop ends, as shown in Fig. 16. These two gripping or clamping jaws are moved away from the supporting head 44 when the sizing mandrel is contracted and thereby permit the operator to freely remove one hoop from the mandrel and replace the same by another. During the initial portion of each cycle of operations of the machine and before the sizing and locking operations are effected the two clamping jaws 45, 46 move inwardly or rearwardly so as to grip the hoop and remain in this position until the sizing and locking of the hoop has been effected after which these jaws are again moved outwardly or forwardly into an inoperative position. By providing the left hand clamping jaw engaging the inner hoop end with a smooth face and the right hand gripping jaw engaging the outer hoop end with a rough face the outer hoop end will be held against longitudinal movement but the inner hoop end will be permitted to slide lengthwise relatively to the outer hoop end during the sizing operation. It is therefore possible for the operator to place the extremity of the outer hoop end in a definite position relative to a gage or mark on the supporting head or other part of the machine so that the first rivet from the extremity of the outer hoop end will be always placed at a predetermined distance from this extremity and thereby insure a uniform and neat appearance of the hoop according to accepted standards of construction.

The operation of the clamping arms is effected so that the pressure which they exert against the hoop ends is of a yielding character and thereby not only permit of

slight variations in the thickness of the hoops but also avoid breakage in the machine without requiring great nicety of adjustment. In its preferred form the means for operating the clamping or gripper jaws 70 for accomplishing this purpose are constructed as follows:

47, 48 represent two upright clamping arms which are arranged on the front part of the machine on opposite sides of the center thereof and adapted to swing back and forth lengthwise of the machine. 49 represents a horizontal clamping shaft which is journaled transversely in suitable bearings on the upper front part of the main frame 75 so as to be capable of a rocking movement. Each of the clamping arms is mounted yieldingly at its lower end on this shaft, the preferred means for this purpose consisting of a sleeve 50 secured to the clamping shaft 80 and provided with a downwardly and forwardly projecting lug 51 to which the lower end of the respective clamping arm is pivoted by means of a bolt 52 or the like, a tension rod 53 connected at one end with the sleeve 50 and passing through an opening in the lower part of the respective clamping arm, and a spring 54 surrounding the tension rod and bearing at its inner end against the outer side of the clamping arm while its outer end bears against a screw nut 55 at the outer end of the tension rod. The movement of the clamping arm under the action of this spring may be adjustably controlled by means of a stop screw 85 56 arranged on the lower part of the clamping arm and engaging with the adjacent part of the supporting sleeve 50. The rock shaft 49 is turned in the direction for moving the clamping jaws 45, 46 rearwardly 95 or inwardly toward the supporting head 44 by means of a rock arm 57 depending from this rock shaft and provided at its lower end with a roller 58 which engages with a rotatable gripper cam 59 mounted on the main shaft, as shown in Figs. 1-4. The return movement of the rock shaft for moving the clamping jaws forwardly or away from the supporting head is effected by 100 means of a spring 60 which connects the cam arm 57 with the rear part of the main frame. During each cycle of operations of the machine the rotary movement of the cam 59 moves the cam arm 57 forwardly thereby moving the clamping jaws rearwardly or 105 inwardly for the purpose of gripping the overlapping ends of the hoop between the clamping jaws and the supporting head. The throw of the cam 59 is so designed that it is in excess of the requirements for engaging the clamping jaws with the hoop ends which excess movement causes the 110 springs 54, 54 of the clamping arms 47, 48 to be strained and a yielding pressure to be applied by their jaws against the over- 115 120 125 130

lapping hoop ends, thereby adapting these jaws to variations in thickness of the hoops or other conditions and also avoiding breakage of any parts, which otherwise would be liable to occur.

5 After the overlapping ends of the hoop have been clamped and sized the devices which produce the lock joint or connection between the hoop ends operates upon the latter, which mechanism is preferably constructed as follows:

10 61 represents a stationary supporting block, preferably of rectangular form, arranged in a recess 62 in the front or outer side of the supporting head and held therein, preferably, by means of set screws 63 arranged in the upper part of the supporting head and engaging with the upper side of this supporting block. The front side or 15 outer face of this supporting block is flush, or substantially so, with the front face of the supporting head and preferably curved concentrically with the face of the latter and the upright flanges of the front mandrel section. In the front side of this supporting block the same is provided with two sockets 64, 64 which are arranged horizontally side by side but spaced apart and in each of these 20 sockets is arranged an abutment die 65 of hard material such as steel. Each of these abutment dies is preferably of tubular form and has its front end extending slightly beyond the face of the companion supporting block. The abutment dies are held in their 25 sockets by means of set screws 66 arranged in the lower part of the supporting block and engaging with the undersides of the abutment dies. The overlapping ends of the hoop are placed by the operator in front of 30 these abutment dies preparatory to forming the lock joint between the same. In order to reliably support and retain these overlapping hook ends in front of these abutment dies and prevent the same from 35 becoming twisted or assuming a scissor-like position relatively to each other preparatory to forming the lock joint between the same a support is provided for the same which 40 preferably consists of a forwardly projecting flange or shelf 67 arranged at the lower end of this supporting block in position to engage the lower edges of the hoop ends so that the latter are retained parallel and 45 in a straightened position relatively to each other and also supported so that the same are arranged midway of their height in line with the abutment dies, as shown in Fig. 6. 50 68, 68 represent two forming dies, preferably of tubular shape, which are arranged 55 horizontally side by side and which are movable toward and from the outer side of the hoop in line with the abutment dies for the purpose of clamping the overlapping hoop ends between the abutment and forming dies or releasing the same. While the

60 forming dies are moved inwardly against the outer side of a hoop so that the overlapping ends of the latter are clamped between the abutment and forming dies, two tubular rivets are formed side by side out 70 of the stock of the overlapping hoop ends, each of these rivets having an integral tubular part which projects from the inner hoop end outwardly through an opening in the outer hoop end. These rivets are 75 produced by means of two punches or needles 69 which are arranged horizontally side by side and parallel lengthwise of the machine and guided in correspondingly arranged openings 70 formed in the supporting head 80 and extending at their front ends through openings 71 in the fixed supporting block and into the abutment dies. The rear ends of these punches project beyond the inner side of the supporting head. In the retracted position of the punches the outer or front ends of the same are arranged in rear of the faces of the abutment dies and after the overlapping hoop ends are clamped between the abutment and forming dies the 85 punches are moved outwardly and forced through the metal of the overlapping hoop ends so as to form two pairs of eyelets thereon, the members of each pair being arranged one within the other and projecting 90 outwardly into the bore of one of the forming dies, as shown in Fig. 7. This outward or forward movement of the punches may be produced by various means but preferably by the means which are shown in the 95 drawings and which comprise a rock shaft 100 72 journaled transversely in the upper part of the main frame, a punch lever comprising an upper arm 73 secured to the punch rock shaft and projecting upwardly through 105 an opening 74 formed in the table of the frame between the front and rear mandrel sections and a lower rock arm 75 secured to the punch rock shaft and projecting downwardly therefrom, two bearing pieces 76, 76 110 secured to the front side of the upper punching arm 73 and engaging with the rear ends, respectively, of the punches, and a punching cam 77 arranged on the main or cam shaft and engaging with a roller 78 115 on the lower arm of the punching lever, as shown in Figs. 2 and 4. As the high part of the punching cam engages with the lower arm of the punching lever the upper arm of the latter is moved forwardly for causing the two punches to perforate the overlapping hoop ends and form the tubular rivets or eyelets thereon and when the lower part of this cam is presented to the lower punching arm the latter returns by gravity 120 to its retracted position together with the upper arm thereof which is connected therewith through the medium of the rock shaft 72.

125 After the punches have formed the tu- 130

tular rivets on the overlapping hoop ends the forming dies are moved away from the outer side of the hoop and then two clenching dies 79 operate upon the rivets of the 5 hoop ends while the latter are still resting on the shelf 67 and arranged in front of the abutment dies. These clenching dies are arranged horizontally side by side and spaced apart a distance equal to that between the forming dies and between the 10 abutment dies. After the forming dies have been withdrawn from the outer side of the hoop the same are moved upwardly and at the same time the clenching dies are 15 raised into a position in which they are in line respectively with the abutment dies, as shown in Fig. 8. After this the clenching dies are moved inwardly into engagement with the front ends of the tubular rivets of 20 the hoop ends so that each of these rivets is up-set or clenched at its front end laterally against the outer side of the outer hoop end, as shown in Fig. 9. The front ends of the tubular rivets are compelled to spread 25 and up-set against the outer side of the hoop by means of retaining stems 80, 80 arranged centrally on the faces of the clenching dies, respectively. Each of these stems is adapted to engage with the front end of one of 30 the perforating punches in one of the tubular rivets and push the respective punch backwardly out of the rivet and into the companion abutment die so that as the punch is withdrawn from the respective tubular rivet the retaining stem enters the 35 same and thereby provides a continuous support for the rivet in its bore which operates as a core to prevent the front end of the tubular rivet from turning inwardly but 40 instead insures turning the same laterally against the outer side of the hoop.

After the rivets have been thus up-set or clenched the clenching dies are again withdrawn forwardly from the hoop and abutment dies to permit the operator to remove the finished hoop and replace the same by another and the forming and clenching dies are again lowered while in this retracted position preparatory to beginning another 45 cycle of operations of the machine in which position the forming dies are again arranged opposite the abutment dies and the clenching dies are arranged below and out of line with the abutment dies, as shown in Fig. 6. 50 55 The forming and clenching dies may be alternately moved laterally relatively to the abutment dies and punches and also successively moved toward and from the abutment dies and punches by various means but preferably by the means which are shown in the drawings and constructed as follows:

60 65 81 represents a movable or vibratory supporting block upon which the forming and clenching dies are mounted preferably by providing the face of this block with sock-

ets 82, 83 in which these dies are secured so that their faces are either flush with or project slightly beyond the face of this block, as shown in Figs. 6-9. This movable supporting block is preferably constructed of 70 dove-tail form in cross section and seated in a correspondingly shaped socket 84 which is formed on the free inner end of a vertically swinging shifting arm 85 and retained therein by the set screw 86 arranged on the 75 upper part of this arm and engaging with the upper side of this block, as shown in Fig. 6. Upon raising or lowering this shifting arm while the forming dies and clenching dies are in their retracted or inner inoperative position either one or the other of these pairs of dies may be brought to the operative position in line with the abutment dies and punches. The outer end of the shifting arm is pivoted by means of a horizontal transverse pin 87 to the upper arm 88 of a main die or forming lever 89 which latter is mounted on a horizontal shaft 90 journaled transversely in suitable bearings on the upper front part of the machine while 90 its lower arm 91 is provided with a roller 92 which engages with a cam 93 on the adjacent part of the main shaft. This cam has two high faces and two low faces which alternate and form a double throw cam which 95 operates to rock the forming lever twice during each cycle of operations of the machine. The return movement of this lever when its roller 92 stands opposite the low parts of the cam 93 is effected by means of a spring 94 100 connecting the lower arm of this lever with a bracket 95 secured to the rear part of the frame, as shown in Fig. 4. The vertically swinging movement of the die shifting arm 85 on the upper arm of the forming lever 105 110 may be limited by various means but preferably by upper and lower stops 96, 97 arranged on the upper and lower part of the upper forming lever arm and adapted to be engaged alternately by the upper and lower sides of the shifting arm 85. In the position of the parts shown in Fig. 6, this shifting arm is in its lowered position in which the same engages the lower stop 97 of the forming lever and the forming dies are in 115 their operative position relatively to the abutment dies and punches, while in Fig. 8 this shifting arm 85 is in its elevated position and in engagement with the upper stop 96 of the forming lever so that the clenching dies are in the operative position relatively to the abutment dies and punches. This shifting arm is either in its elevated or its lowered position whenever the main forming lever is rocking and carrying either 120 the forming dies or the clenching dies toward and from the abutment dies and punches but when the forming lever is in its retracted position and the forming dies and punches are out of engagement with the 125 130

abutment dies and punches then the shifting arm 85 is free to be rocked vertically for alternating the position of the forming and clenching dies relatively to the abutment dies and punches.

When the high part of the cam 93 shown uppermost in Fig. 4 engages the roller 92 of the lever 91 then the lower arm of the latter is moved outwardly and the upper 10 arm thereof inwardly so that the die block 81 is moved into the position shown in Fig. 7, and when the high part of the cam 93 shown in the lower part of Fig. 4 engages the roller 92 of the lever 91, then the latter is shifted 15 for carrying the die block 81 into the position shown in Fig. 9, it being understood that this die block is also shifted vertically from the position shown in Fig. 7 to the position shown in Fig. 9 during alternate rocking 20 movements of the lever 91. The means whereby this alternation of the forming and clenching dies relative to the working position is effected may be accomplished by mechanism which may be variously constructed but the means which are shown in the drawings have been found satisfactory in actual operation and as there shown the same are constructed as follows:

98 represents an upright shifting rod 30 which is pivotally connected at its upper end with one side of the shifting arm 85. 99 represents an intermediate tappet lever pivoted to swing vertically by means of a pin 100 on the lower arm 91 of the forming lever. The 35 front arm of this tappet lever is operatively connected with the lower end of the shifting rod 98 while the rear or inner arm of the same is adapted to be engaged by means of a tappet or auxiliary cam 101 which rotates 40 with the main shaft 20 and is preferably mounted on one side of the forming cam 93. The shifting arm 85 is rocked once during each cycle of operations. While the upper arm of the forming lever is effecting its first 45 forward and backward movement under the action of the high and low faces of the double throw cam 93 the shifting arm 85 is retained in its lowermost position by means of the spring 102 connecting the shifting rod 50 98 with the adjacent part of the forming lever at which time the tappet 101 is out of engagement from the tappet lever 99 but during the interval between the first return stroke of the main lever and its second forward 55 stroke the tappet 101 operates the tappet lever 99 so as to raise the shifting arm 85 relatively to the main lever and retain the same in this elevated position during the next forward and backward stroke of the 60 main lever. By this means the main lever 89 is rocked twice during each cycle of operations of the machine while the shifting arm 85 is rocked but once during this time so that during the first forward movement of 65 the main lever the forming dies are moved

toward the abutment dies and punches and during the next forward movement of the main lever the clenching dies are moved toward the abutment dies and punches, which alternate shifting of the forming and clenching dies to the operative position is effected 70 during each cycle of operations of the machine.

In order to hold the shifting arm 85 firmly and reliably in its proper elevated or depressed position without requiring any fine fitting of the tappet 101 or the parts associated therewith the means for raising the shifting arm 85 are so constructed that a yielding pressure in an upward direction is 75 applied to this shifting arm which is preferably effected by means of a yielding connection between the lower end of the shifting rod 98 and the front end of the tappet lever 99, which connection in its preferred 80 form consists in providing the front arm of the tappet lever with an opening through which the lower end of this shifting rod extends and providing a spring 103 which surrounds this shifting rod and bears with its 85 upper end against a collar 104 on this rod and with its lower end against a sleeve 105 resting on the upper side of the front arm of the tappet lever, the lower end of said 90 sleeve being bifurcated, as shown in Figs. 1 95 and 4. At its lower end the shifting rod 98 is provided with a washer 106 engaging with the underside of the front arm of the tappet lever and held adjustably in place on this rod by means of screw nuts 107. When the rear 100 arm of the tappet lever is engaged by the tappet 101 the shifting arm 85 is raised until it engages with the upper stop 96 of the main lever and thereafter any excess throw of this tappet causes the spring 103 to be compressed 105 without further shifting the arm 85 upwardly, thereby avoiding exact fitting of the tappet 101 for effecting this movement. Any accurate adjustment which may be necessary 110 to bring the forming and clenching dies into their proper operative position may be effected by providing each of the stops 96, 97 with an outwardly projecting lug 108 which is adjustably secured to the upper arm of the main lever by means of a bolt 109 and inserting shims 110 of greater or less thickness 115 between the backs of these stops and the adjacent surface of the main lever, as shown in Figs. 1, 2, 4 and 6.

For some purposes it may be sufficient to merely provide a hoop with one rivet in which case only one set of forming and upsetting devices need be employed but if desired, more than two sets of rivet forming devices may be used when a greater number 125 of rivets are required. Instead, however, of connecting the overlapping hoop ends by more than two rivets it is preferable to provide the same between the two rivets with one or more interlocking hooks which are 130

constructed like those shown in Figs. 15, 16 and 17 and which operate to increase the resistance which the hoop ends are capable of exerting against any strains tending to pull them apart lengthwise relatively to each other. Such interlocking hooks are preferably formed on the overlapping hoop ends at the same time that the upsetting or clenching of the rivets is effected by providing the coöoperating faces of the fixed and movable supporting blocks with coöperating cutters 111, 112. Each of these cutters is preferably provided on its face or outer side with a plurality of cutting teeth or blades 113 which are adapted to coöperate with the corresponding blades or teeth of the other cutter when the two supporting blocks approach each other while these cutters are in their proper relative position. The cutter 20 of the fixed supporting block is arranged in a horizontal groove 114 formed in this block between the sockets which contain the abutment dies and the cutter of the movable supporting block is arranged in a horizontal 25 groove 115 arranged in the face of this last mentioned block between the sockets containing the clenching dies, as shown in Figs. 10-14. The cutter associated with the clenching dies is held in place by pressing the latter against opposite ends of the respective cutter by means of set screws 116 arranged in opposite ends of the movable supporting block and engaging with the outer sides of the clenching dies, as 30 shown in Fig. 12, while the cutter of the fixed supporting block is retained in place by means of a set screw 117 arranged in the lower part of the fixed supporting block and engaging with the underside of the cutter 35 therein, as shown in Fig. 14.

A controlling mechanism is provided for this machine which is so constructed that it is necessary for the operator to perform a manual operation for beginning each cycle 45 of operations of the machine but which automatically stops the machine at the end of each cycle of operations and also prevents the manual shifting mechanism from being maintained constantly in a depressed position, thereby preventing the machine from running continuously. The preferred form 50 of this mechanism is shown in Figs. 1, 2 and 3 and is constructed as follows:

118 represents a driven gear wheel which 55 is mounted loosely on one end of the main or cam shaft of the machine, preferably the right hand end thereof, and which is rotated continuously by means of a horizontal driving shaft 119 journaled transversely in 60 suitable bearings on the rear lower part of the frame and provided with a pinion 120 which meshes with the gear wheel 118 and also provided with a pulley 121 adapted to receive a belt for transmitting motion to the 65 driving shaft from any suitable source. A

clutch is provided between the main shaft 20 and the gear wheel 118 for the purpose of connecting and disconnecting these parts and either operating or stopping the machine. In its preferred form this clutch comprises a 70 clutch wheel 122 loosely mounted on the main shaft 20 and secured to the inner side of the gear wheel 118 and provided on its periphery with a plurality of clutch teeth 123 each of which has an abrupt front face 75 and an inclined rear face. 124 represents a bracket secured to the main shaft between the clutch wheel and the adjacent bearing of the main frame and provided on one side of the shaft with a bearing in which a spindle 80 or short shaft 125 is journaled parallel with the main shaft. To the outer end of this spindle is secured a vertically swinging coupling or clutch dog 126 having a rearwardly projecting nose 127 and a forwardly 85 projecting curved tail 128. This dog may be turned so as to move its nose laterally out of the path of the clutch teeth so that the clutch wheel and driving mechanism moves idly without operating the main shaft and the mechanism operatively connected therewith, but when the nose of the coupling dog is moved inwardly into the path of the clutch teeth one of the latter will engage its abrupt front side with the nose of the dog and thereby couple the driving shaft and the main shaft for operating the machine. The clutch dog is turned in the direction for engaging its nose with a tooth of the clutch wheel by means of a spring 160 connected at 90 one end with the lower part of the bracket 124 while its opposite end is connected with an arm 129 secured to the inner end of the clutch spindle 125, as shown in Figs. 1 and 3. Disengagement of the nose of the dog 95 from the clutch teeth is effected by a trip mechanism operating upon the curved tail of the dog which trip mechanism comprises a vertically swinging rock arm 130 provided at its free end with a trip roller 131 100 adapted to move into and out of the path of the tail of the clutch dog. This trip arm is mounted on a horizontal rock shaft 132 which is journaled lengthwise on the outer side of the right side piece of the main frame 110 and is provided with an upright operating arm 133. 134 represents a vertically swinging intermediate rock lever which is arranged transversely of the main frame and pivoted thereto by means of a bolt 135, as 115 shown, or by any other suitable means. The outer arm of this intermediate lever is connected by means of a link 136 with the upright arm 133 of the rock shaft 132 while its inner arm is connected with the main frame 120 by means of a spring 137 which constantly tends to raise this inner arm and thereby turn the elbow lever composed of the shaft 132 and the arms 130, 133, so that the trip roller 131 is arranged in the path of the tail 130

of the dog and causes the latter to be turned in the direction which will move the nose of this dog out of engagement from the teeth of the clutch wheel. The swinging movement 5 of this intermediate lever under the action of the spring 137 is limited by means of a stop 138 which preferably consists of a screw mounted on the adjacent part of the frame in position to be engaged by the underside 10 of the outer arm of the intermediate lever which operates to arrest this lever in the position in which the pivotal connection between the link 136 and the outer arm of the intermediate lever and the upper arm of the 15 elbow lever are in line with the pivot of the intermediate lever, thereby forming a toggle at this time which rigidly holds the trip roller 131 in its lowered operative position so that the same will firmly engage 20 the tail of the dog and move its nose out of engagement from the teeth of the clutch wheel.

139 represents an upright shifting rod which is guided with its upper part in a 25 bracket 140 on the main frame and provided at its upper end with a handle 141 while its lower end engages with the inner arm of the intermediate lever 134. This shifting rod is normally held in an elevated position by 30 means of a spring 142 surrounding the upper part of the shifting rod and engaging its upper end against the underside of the handle while its lower end bears against the bottom of a pocket 143 formed in the upper side 35 of this bracket. The length of this spring is such that when the same is fully relaxed this shifting rod is raised into its highest position in which its lower end is close to the upper side of the inner arm of the intermediate 40 lever 134, as shown in Fig. 1. When the operator depresses the shifting rod the intermediate lever 134 is turned so as to unfold or break the toggle connection between the same and the elbow-shaped trip lever, 45 whereby the trip roller 131 is raised and the spring 128 is permitted to throw the nose of the dog inwardly into the path of the teeth of the clutch wheel, thereby coupling the main shaft with the driving shaft and causing 50 the machine to begin a cycle of operations. If the operator immediately withdraws his hand from the shifting rod 139 so as to permit the spring 142 to raise the same and the spring 137 to turn the intermediate lever in the direction for again lowering the trip roller 131, then the tail of the coupling dog after making one complete rotation about the axis of the machine shaft 55 will engage this trip roller and be pressed inwardly thereby, so that the nose of the dog is disengaged from the clutch wheel, thereby uncoupling the operating mechanism from the driving mechanism and automatically stopping the same at the end of a complete cycle of operations.

It is desirable to provide means which will prevent continuous operation of the machine by holding the shifting rod 139 continuously in a depressed position inasmuch as such continuous operation might 70 injure the machine if the operator failed to remove a finished hoop from between the co-operating dies. In order to reduce the possibility of such an occurrence to a minimum means are provided whereby the shifting 75 rod 139 is automatically disengaged from the intermediate lever during the initial portion of each cycle of operations of the machine if the operator should neglect to take his hand off the shifting rod. The preferred means for this purpose comprise a guide bracket 144 which is mounted on the main frame adjacent to the lower part of the shifting rod 139 and provided with a horizontal longitudinal slot 145 through 80 which the lower part of this rod passes. Within a pocket 146 in this bracket is arranged a spring 147 which constantly tends to move the shifting rod laterally toward the inner end of the slot 145 in which the same is arranged with its lower end over the inner arm of the intermediate lever 134, as shown in Fig. 3. 148 represents a tappet or knock-off pin arranged on the lower arm of the main or forming lever 89 and 85 projecting laterally therefrom into a position in rear of the lower part of the shifting rod 139, as shown in Figs. 1 and 3. After the machine begins its cycle of operations due to the manual depression of 90 this shifting rod and the coupling of the clutch between the main shaft and the driving shaft, the tappet 148 while moving forwardly with the lower arm of the lever 89 causes the lower part of the shifting rod 139 to be moved forwardly and out of line with 95 the front arm of the intermediate rock lever 134. If therefore this shifting rod has been held in a depressed position after the coupling operation has taken place and the machine has started, the forward movement of the shifting rod 139 under the action of the tappet 148 will cause this shifting rod to be knocked off or disengaged from the intermediate lever and permit the latter to 100 immediately return to its normal position 105 under the action of the spring 137 so that the trip roller 131 is in position to uncouple the clutch and stop the machine at the end of the cycle of operations. It will therefore be apparent that by this means it is necessary for the operator to first permit this shifting rod to be raised into its highest position by the spring 142 in order to 110 permit the spring 147 to again carry the lower end of the shifting rod backwardly over the inner arm of the intermediate lever before the trip roller 131 can be again raised 115 to permit of coupling the clutch. Inasmuch as the main rock lever 89 makes two oscil- 120 125 130

lations during each cycle of operations of the machine, the tappet 148 moves or knocks off the lower end of the shifting rod 139 from the intermediate lever twice during each cycle of operations, thereby reducing to a minimum the chances of operating the machine continuously if the attendant through oversight or carelessness should depress the shifting rod 139 at an improper time.

The weight of the rotating parts of the machine, in the absence of any provision to prevent it, would be liable at times to overthrow or move the mechanism slightly beyond a complete cycle of operations and thereby interfere with the operation of the machine as well as the insertion and removal of hoops. In order to avoid such overthrow means are provided which preferably comprise a stop cam 149 fixed on the main shaft and provided in its salient part with a notch 150, an elbow lever 151 pivoted on the main frame and provided on one of its arms with a roller 152 adapted to engage with the face of the stop cam and a spring 153 connecting the main frame with the other arm of the elbow stop lever. The construction of the stop cam and the position of the stop roller are so determined that when the machine reaches the end of its cycle of operations the notch of the cam 149 will be presented to the roller 152 and the latter will be pressed with sufficient force into this notch by means of the spring 153 so as to reliably stop the operation of the machine at this time and prevent the objectionable overthrow above referred to.

This machine as a whole is very reliable and efficient in operation and permits of the expeditious production of a large number of locked sheet metal hoops at comparatively low cost.

I claim as my invention:

1. A machine for locking the ends of metal hoops comprising a forming punch adapted to perforate the overlapping ends of the hoop and produce an integral rivet thereon, a female forming die adapted to receive said punch and rivet, and a clenching die adapted to upset the end of said rivet against said hoop, said forming and clenching dies being movable laterally relatively to the axis of the punch for bringing the forming and clenching dies successively into operative relation to said punch.

2. A machine for locking the ends of metal hoops comprising a forming punch adapted to perforate the overlapping ends of the hoop and produce an integral rivet thereon, a female forming die adapted to receive said punch and rivet, a clenching die adapted to upset the end of said rivet against said hoop, and an abutment die which is adapted to engage with the hoop opposite the forming and clenching dies,

said forming and clenching dies being movable laterally relatively to the axis of the punch for bringing the forming and clenching dies successively into operative relation to said punch.

3. A machine for locking the ends of metal hoops comprising a forming punch adapted to perforate the overlapping ends of a metal hoop and produce a tubular rivet extending from one hoop end through the other, a tubular abutment die through which said punch passes and which is adapted to engage with the same side of the hoop as the punch, a tubular forming die which receives said punch and rivet and is adapted to engage with the opposite side of the hoop, and a clenching die adapted to upset the front end of said rivet, said forming and clenching dies being movable laterally relatively to the axis of the punch for bringing the forming and clenching dies successively into operative relation to said punch.

4. A machine for locking the ends of metal hoops comprising a forming punch adapted to perforate the overlapping ends of a metal hoop and produce a tubular rivet extending from one hoop end through the other, a tubular abutment die through which said punch passes and which is adapted to engage with the same side of the hoop as the punch, a tubular forming die which receives said punch and rivet and is adapted to engage with the opposite side of the hoop, a clenching die adapted to upset the front end of said rivet and provided with a retaining stem adapted to enter the rivet from the front end thereof, said forming and clenching dies being movable laterally relatively to the axis of the punch for bringing the forming and clenching dies successively into operative relation to said punch.

5. A machine for locking the ends of metal hoops comprising a forming punch adapted to perforate the overlapping ends of a metal hoop and produce a rivet extending from one hoop end through the other, a forming die which receives the front end of said rivet, a clenching die adapted to upset the front end of said rivet, a stationary guide for said punch, a shifting rock arm supporting said forming and clenching dies, and a main rock lever on which said shifting arm is mounted.

6. A machine for locking the ends of metal hoops comprising a forming punch adapted to perforate the overlapping ends of a metal hoop and produce a rivet extending from one hoop end through the other, a normally stationary abutment die arranged adjacent to said punch, a forming die which receives the front end of said rivet, a clenching die adapted to upset the front end of said rivet, a normally stationary supporting block which supports said abutment die, and a vibratory supporting block which is movable laterally

relatively to the punch and abutment die and which supports said forming die and clenching die.

7. A machine for locking the ends of metal hoops comprising a forming punch adapted to perforate the overlapping ends of a metal hoop and produce a rivet extending from one hoop end through the other, a forming die which receives the front end of said rivet, 10 a clenching die adapted to upset the front end of said rivet, a stationary guide for said punch and a support for said forming and clenching dies which is movable laterally relatively to said punch and also lengthwise 15 relatively to the punch.

8. A machine for locking the ends of metal hoops comprising a forming punch adapted to perforate the overlapping ends of a metal hoop and produce a rivet extending from one 20 hoop end through the other, a forming die which receives the front end of said rivet, a clenching die adapted to upset the front end of said rivet, a normally stationary supporting block which supports said abutment die, 25 and a vibratory supporting block which is movable laterally relatively to the punch and abutment die and which supports said forming die and clenching die and which is also movable lengthwise for bringing said forming die and clenching die successively in operative engagement with said hoop in line 30 with said punch and abutment die.

9. A machine for locking the ends of metal hoops comprising a forming punch adapted 35 to perforate the overlapping ends of a metal hoop and produce a rivet extending from one hoop end through the other, a forming die which receives the front end of said rivet, a clenching die adapted to upset the front end of said rivet, a stationary guide for said punch, a frame on which said punch guide is mounted, a shifting arm carrying 40 said forming and clenching dies, and a lever on which said arm is pivoted and which is pivotally mounted on the main frame. 45

10. A machine for locking the ends of metal hoops comprising a forming punch adapted to perforate the overlapping ends of a metal hoop and produce a rivet extending 50 from one hoop end through the other, a forming die which receives the front end of said rivet, a clenching die adapted to upset the front end of said rivet, a stationary guide for said punch, a frame on which said punch guide is mounted, a shifting arm carrying 55 said forming and clenching dies, and a lever on which said arm is pivoted and which is pivotally mounted on the main frame, the axes of said arm and lever being parallel. 60

11. A machine for locking the ends of metal hoops comprising a forming punch adapted to perforate the overlapping ends 65 of a metal hoop and produce a rivet extending from one hoop end through the other, a

forming die which receives the front end of said rivet, a clenching die adapted to upset the front end of said rivet, a stationary guide for said punch, a frame on which said punch guide is mounted, a shifting arm carrying 70 said forming and clenching dies, a lever on which said arm is pivoted and which is pivotally mounted on the main frame, a rotary cam mounted on the main frame and operating on said lever to move 75 the same in the operating direction, and a spring for moving said lever in the opposite direction.

12. A machine for locking the ends of metal hoops comprising a forming punch 80 adapted to perforate the overlapping ends of a metal hoop and produce a rivet extending from one hoop end through the other, a forming die which receives the front end of said rivet, a clenching die adapted to upset 85 the front end of said rivet, a stationary guide for said punch, a frame on which said punch guide is mounted, a shifting arm carrying said forming and clenching dies, a main lever on which said arm is pivoted and which is pivotally mounted on the main frame, and means for operating said arm comprising a tappet lever mounted on said main lever, a rod for transmitting motion from said tappet lever to said shifting arm, 90 a spring for moving said rod, shifting arm and tappet lever in one direction, and a rotatable tappet operating on said tappet lever for moving the same and the parts associated therewith in the opposite direction. 95

13. A machine for locking the ends of metal hoops comprising a forming punch adapted to perforate the overlapping ends of a metal hoop and produce a rivet extending from one hoop end through the other, 100 a forming die which receives the front end of said rivet, a clenching die adapted to upset the front end of said rivet, a stationary guide for said punch, a frame on which said punch guide is mounted, a shifting arm carrying 105 said forming and clenching dies, a lever on which said arm is pivoted and which is pivotally mounted on the main frame, means for rocking said main lever twice during each cycle of operations of the machine, and means for rocking said shifting arm once during each cycle of operations of the machine. 110

14. A machine for locking the ends of metal hoops comprising a forming punch 120 adapted to perforate the overlapping ends of a metal hoop and produce a rivet extending from one hoop end through the other, a forming die which receives the front end of said rivet, a clenching die adapted to upset 125 the front end of said rivet, a stationary guide for said punch, a frame on which said punch guide is mounted, a shifting arm carrying said forming and clenching dies, a lever on which said arm is pivoted 130

and which is pivotally mounted on the main frame, means for operating said main lever comprising a main rotatable cam engaging said lever, and means for operating said shifting arm comprising a tappet mounted on the main lever and operatively connected with the shifting arm, and a tappet arranged on said main cam and engaging with said tappet lever.

15. A machine for locking the ends of metal hoops comprising a forming punch adapted to perforate the overlapping ends of a metal hoop and produce a tubular rivet extending from one hoop end through the other, a tubular abutment die through which said punch passes and which is adapted to engage with the same side of the hoop as the punch, a tubular forming die which receives said punch and rivet and is adapted 20 to engage with the opposite side of the hoop, a clenching die adapted to upset the front end of said rivet, a stationary block which supports said abutment die, a vibratory block which is movable toward and 25 from said stationary block and supports said forming and clenching dies, a shifting rock arm which carries said vibratory block, a main lever on which said shifting arm is pivoted, and stops on said lever which limit 30 the rocking movement of said arm on said lever.

16. A machine for locking the ends of metal hoops comprising a forming punch adapted to perforate the overlapping ends 35 of a metal hoop and produce a tubular rivet extending from one hoop end through the other, a tubular abutment die through which said punch passes and which is adapted to engage with the same side of the hoop as the punch, a tubular forming die which receives said punch and rivet and is adapted 40 to engage with the opposite side of the hoop, a clenching die adapted to upset the front end of said rivet, a stationary block which supports said abutment die, a vibratory block which is movable toward and 45 from said stationary block and supports said forming and clenching dies, a shifting rock arm which carries said vibratory block, a main lever on which said shifting arm is pivoted, stops on said lever which limit 50 the rocking movement of said arm on said lever, and means for operating said arm comprising a shifting rod connected with 55 said shifting arm, a sleeve capable of sliding lengthwise on said rod, a spring for yieldingly transmitting motion from said sleeve to said rod, a tappet lever engaging with said sleeve, and a tappet engaging with 60 said tappet lever.

17. A machine for locking the ends of metal hoops comprising means for producing rivets on the overlapping ends of a hoop for connecting the same, and means 65 for holding said ends in position during

the operation of forming said rivets comprising a fixed support adapted to be engaged by one side of the hoop, a clamping jaw movable toward and from the opposite side of the hoop, a clamping lever one arm 70 of which carries said jaw, a cam engaging the other arm of said lever for moving the same in the operative direction, and a spring for moving said clamping lever in the opposite direction. 75

18. A machine for locking the ends of metal hoops comprising means for producing rivets on the overlapping ends of a hoop for connecting the same, means for holding said ends in position during the 80 operation of forming said rivets, and means for operating said holding means which are yielding in the operating direction and which comprise a gripper rock arm which carries said holding means, a cam rock arm 85 to which said gripper arm is pivoted, a tension rod connected with said cam arm, a spring operating to transmit a yielding pressure from said tension rod to said gripper arm, and a cam engaging with said cam 90 arm.

19. A machine for locking the ends of metal hoops comprising means for producing rivets on the overlapping ends of a hoop for connecting the same, means for holding said ends in position during the 95 operation of forming said rivets, and means for operating said holding means which are yielding in the operating direction and which comprises a gripper rock arm which 100 carries said holding means, a cam rock arm to which said gripper arm is pivoted, a tension rod connected with said cam arm, a spring operating to transmit a yielding pressure from said tension rod to said gripper arm, a stop screw mounted on said gripper arm and adapted to engage said cam arm, and a cam engaging with said cam arm. 105

20. A machine for locking the ends of metal hoops comprising means for producing rivets on the overlapping ends of a hoop for connecting the same, and means for holding said ends in position during the 110 operation of forming said rivets comprising a fixed support adapted to be engaged by one side of the hoop and two clamping jaws movable toward and from the other side of the hoop and to engage the latter on opposite sides of the rivet producing means, one of said jaws having a comparatively smooth face adapted to engage one end of the hoop adjacent to the opposite end thereof and the other clamping jaw having a comparatively rough face adapted to engage the overlapping parts of the hoop ends. 115

21. A machine for locking the ends of metal hoops comprising means for producing rivets on the overlapping ends of a hoop for connecting the same, and means for ad-

justing the size of the hoop preparatory to locking together the ends thereof comprising a plurality of mandrel sections adapted to engage with the inner side of the hoop and one movable with respect to another, and means for actuating the movable mandrel section comprising a lever operatively connected with said movable mandrel section, and a cam engaging said lever.

22. A machine for locking the ends of metal hoops comprising means for producing rivets on the overlapping ends of a hoop for connecting the same, and means for adjusting the size of the hoop preparatory to locking together the ends thereof comprising a plurality of mandrel sections adapted to engage with the inner side of the hoop and one movable with respect to another, and means for actuating the movable mandrel section comprising a lever operatively connected with said movable mandrel section, a cam engaging said lever and adapted to move the same in the operating direction, and a spring for moving said lever in the opposite direction.

23. A machine for locking the ends of metal hoops comprising means for producing rivets on the overlapping ends of a hoop for connecting the same, and means for adjusting the size of the hoop preparatory to locking together the ends thereof comprising a plurality of mandrel sections adapted to engage with the inner side of the hoop and one movable with respect to another, and means for yieldingly moving said movable mandrel section radially relatively to the other section.

24. A machine for locking the ends of metal hoops comprising means for producing rivets on the overlapping ends of a hoop for connecting the same, and means for adjusting the size of the hoop preparatory to locking together the ends thereof comprising a plurality of mandrel sections adapted to engage with the inner side of the hoop and one movable with respect to another, and means for yieldingly moving said movable mandrel section radially relatively to the other section comprising a rock arm having

an inner section which is pivotally mounted 50 on a support and an outer section which is pivoted on said inner section and operatively connected with said movable mandrel section, a tension rod connected with said inner arm section and a spring mounted on 55 said rod and operating to draw said inner and outer arm sections together.

25. A machine for locking the ends of metal hoops comprising two punches adapted to produce two tubular rivets integrally on their overlapping ends, abutment dies arranged adjacent to said punches, forming dies which receive said rivets and punches, clenching dies adapted to engage the front ends of said rivets and upset the 65 same, and a pair of coöperating cutters adapted to form interlocking hooks on said hoop ends between the rivets thereof, one cutter being arranged between said punches and the other between said clenching dies, 70 and means for causing said punches and former dies to coöperate at one time and said clenching dies and the adjacent cutter to coöperate at another time, respectively, with said abutment dies and the other cutter. 75

26. A machine for locking the ends of metal hoops comprising means for producing rivets out of the overlapping ends of the hoop and connecting said ends, a driving shaft, a clutch adapted to couple and uncouple said shaft and said rivet producing means, manual trip means for rendering said clutch operative, and automatic means for preventing said manual means from being held permanently in its operative position, said manual trip means comprising a rock lever operatively connected with said clutch, a hand operated shifting rod engaging with said lever, a spring for holding said shifting rod yieldingly in operative relation to said rock lever, and a knock-off tappet arranged on the movable part of said rivet forming means and adapted to move said shifting rod out of operation relatively to said lever between the initial part and the 90 end of each cycle of operations of the machine.

EDWIN F. BEUGLER.
